BOMB CONTROL SYSTEM

John Hays Hammond, Jr., Gloucester, Mass.,
assignor to Radio Corporation of America

Application December 18, 1943, Serial No. 514,747

8 Claims. (Cl. 102—2)

1

This invention relates to the detonation of bombs by radiant energy and more particularly to the radio detonation of a plurality of bombs simultaneously.

The invention also provides means for making the detonating mechanism of the bomb inactive for a predetermined time after the bomb has been released.

The invention further provides means for making the radio receiver in the bomb active only during certain predetermined hours of the day for several consecutive days.

The invention also provides means for exploding the bomb automatically at the end of a predetermined time which is preferably several days.

The invention further provides means for automatically exploding the bomb if it is disturbed in the slightest from the position in which it came to rest after hitting the target.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Figure 1 is a section thru the bomb showing the control mechanisms;

Figure 2 illustrates diagrammatically the transmitting circuits on the plane;

Figure 3 illustrates diagrammatically the receiving circuits located in the bomb;

Figure 4 is an enlarged plan view of the sensitive mechanism for detonating the bomb if disturbed; and

Figure 5 is an enlarged sectional view of part of the mechanism shown in Fig. 4.

Like reference characters denote like parts in the several figures of the drawings.

In the following description parts will be identified by specific names for convenience, but they are intended to be as generic in their application to similar parts as the art will permit.

Referring to the accompanying drawings and more particularly to Fig. 1 a bomb 11 is provided with a steel casing 12 to which is attached a hemispherical casing 13 made of plastic or other non-metallic material. Suitable vanes 14 are

2

provided for guiding the bomb in its flight. The interior of the bomb is divided into three compartments 15, 16 and 17 by means of two transverse bulkheads 18 and 19.

5 In the compartment 15 is the explosive charge 21 and a detonator 22. Between the bulkheads 18 and 19 is mounted a cylinder 22' in which slides a cylindrical casing 23. The space between the base of the casing 23 and the bulkhead 18 is filled with sponge rubber 24 or other shock absorbing material.

In the casing 23 is mounted a radio control apparatus 25, a time mechanism 26 and a contact device 27. The radio control apparatus 25 is connected by a flexible conductor 28 to an antenna 29 mounted inside the casing 13. The antenna may be of any suitable non-directive construction and may, if desired, be embedded in the plastic material.

20 The radio control apparatus 25, see Fig. 3, may comprise a radio receiver 31, to which the antenna 29 is connected, a power pack 32, a selector 33 and a relay tube and relay 34. The contacts of the relay 34 are connected to two terminals 35 and 36. The power pack 32 may include a battery 37 and is connected to two terminals 38 and 39.

A suitable transmitter may be provided on the airplane, see Fig. 2, which includes a subaudible oscillator 41, a key 42, a modulator 43, an oscillator amplifier 44 and an antenna system 45.

The time mechanism 26 includes three discs 46, 47 and 48 (Fig. 1), which rotate at varying speeds. For example, the disc 46 may make one revolution in four hours, the disc 47 one revolution in twenty-four hours and the disc 48 one revolution in four days. The disc 46 is provided with a pin 49 and the discs 47 and 48 are provided with conducting sectors 51 and 52 respectively.

40 Engaging the pin 49 is an arm of conducting material 53 which is pivoted at 54. A spring 55 tends to move this arm to the left. Co-operating with the arm 53 are two contacts 56 and 57. Engaging the discs 47 and 48 are two pairs of contacts 58—59 and 61—62 respectively.

The contact mechanism 27 comprises a hemispherical bowl 63 (Figs. 1, 4 and 5) provided with a top 64, the bowl and top being made of nonconducting material. The bowl is secured to a ring 65 which is pivotally mounted in a gimbal ring 66, which in turn is pivotally mounted in brackets 67.

Secured to the ring 65 is a pivot 68, rotatably mounted in the gimbal ring 66, to the end of

which is secured a friction disc 69, see Fig. 5. Mounted on a bracket 71, which is secured to the gimbal ring 66, is a solenoid 72 provided with a core 73. Secured to the core 73 is a collar 74 between which and the solenoid 72 is mounted a compression spring 75. Mounted on the gimbal ring 66 is a spring 76, which is held out of engagement with the friction disc 69 by means of the core 73. A weight 78 mounted on the gimbal ring 66 counterbalances the weight of the 10 solenoid 72, etc.

Secured to the gimbal ring 66 is a pivot 77 where a similar construction is provided including a spring 78 which is controlled by a solenoid 79. The winding of the solenoid 72 is connected by a flexible conductor 81 to one side of a battery 83 and by a flexible conductor 82 to the contact 57. The other side of the battery 83 is connected by a conductor 80 to the arm 53. The winding of the solenoid 79 is connected by branch conductors 84 and 85 to the conductors 81 and 82 respectively.

Mounted in the top 64 of the bowl 63 are four contacts 86 which are connected together and by a flexible conductor 87 to the arm 53. The bowl 63 is filled with mercury 88 or other conducting liquid, to a level just below the contacts 86. Projecting into the mercury 88 is an electrode 89 which is connected by a flexible conductor 91 to the terminal 35. The terminal 36 is connected by a conductor 92 to the contact 56 and the terminals 38 and 39 are connected by conductors 93 and 94 to the contacts 58 and 59 respectively. The contacts 61 and 62 are connected by branch conductors 95 and 96 to the conductors 91 and 92, respectively, which in turn are connected by flexible conductors 97 and 98 and a battery 99 to the detonator 22.

In the operation of this invention when the bomb 11 is released from the airplane the time mechanism 26 is started by any suitable means not shown. When the bomb strikes the target it will not explode, as the circuit to the detonator 22 is open at the contact 56. The sponge rubber 24 will absorb the shock of striking the target so that the mechanisms in the casing 23 will not be damaged. After the bomb has come to rest the contact device 27 will assume a horizontal position, as it is suspended in the gimbal ring 66.

After a predetermined interval of time has elapsed, for example four hours, the disc 46 together with the pin 49 will have rotated sufficiently in a clockwise direction, as indicated by the arrow, to release the arm 53, which will be moved to the left under the action of the spring 55, thus engaging the contacts 56 and 57. This will close a circuit from the battery 83 thru the solenoids 72 and 79, the cores of which will be retracted, thus releasing the springs 76 and 78 which will clamp the contact device 27 in whatever horizontal position it has assumed with respect to the bomb 11. In this position the contacts 86 will be just clear of the surface of the mercury 88.

If any attempt is made to tamper with the bomb and it is moved ever so slightly from the position in which it came to rest the mercury 88 will engage one of the contacts 86 thus completing a circuit from the battery 99 conductors 97 and 91, electrode 89, mercury 88, contact 86, conductor 87, arm 53, contact 56 and conductors 92 and 98 to the detonator 22 which is exploded thus causing the detonation of the explosive charge 21.

If the bomb is not thus exploded the disc 75

47 will rotate in a clockwise direction, as indicated by the arrow, until the segment 51 engages the contacts 58 and 59 which will close the circuit of the battery 37 of the power pack 32. This will put the whole radio control apparatus 25 into a sensitive condition ready to receive signals from the transmitter shown in Fig. 2. This energization may be initiated, for example 20 hours after the bomb has been dropped and may last, for example, for a period of four hours. This active period will recur each day for a predetermined interval of time for a period of several days.

If during this active period a predetermined signal is transmitted from the airplane and is received by the antenna 29 of radio control apparatus 25 will cause the relay circuit 34 to be closed thus completing a circuit from the battery 99, conductors 97 and 91 to terminal 35, relay 20 34, terminal 36, conductors 92 and 98 to the detonator 22, which will be exploded, thus detonating the explosive charge 21.

In this way, all of the bombs, which may have been planted during several bombing raids over a period of several days, may be exploded simultaneously.

The type of radio transmitter depicted in Fig. 2 is assumed to produce a high frequency carrier wave, which is modulated at a lower frequency, which for example may be a subaudible frequency. The receiver shown in Fig. 3 is of a type suitable to selectively receive this signal and cause the operation of the relay 34. It is to be understood, however, that the radio system is not to be limited to this particular type, but may be of any suitable design and construction.

If the bomb is not exploded by radio after a predetermined period, which, for example may be four days, the disc 48 will have rotated in a 40 clockwise direction, as indicated by the arrow, so that the segment 52 will engage the contacts 61 and 62. This will close a circuit from the battery 99, conductors 97 and 95, contact 61, segment 52, contact 62, conductors 96 and 98 to the detonator 45 22 which will be exploded, thus detonating the explosive charge 21.

It is thus seen that a system is provided in which salvos of bombs may be planted on targets on successive days and then all exploded simultaneously by a remote radio signal thus producing a much greater destructive effect than if each of the bombs exploded at the time it struck the target. If, for any reason, it is not possible to explode the bombs by radio they will be automatically exploded at the end of the predetermined period. Meanwhile any attempt to tamper with or remove the bomb will cause it to explode.

Although only a specific form in which this invention may be embodied has been shown herein, 60 it is to be understood that the invention is not limited to any specific construction but may be embodied in various forms without departing from the spirit of the invention as defined by the appended claims.

65 What is claimed is:

1. A bomb comprising a detonator, an electric actuating circuit therefor including a liquid switch means adapted to be closed in response to tilting from a horizontal position, means mounting said liquid switch means for universal movement, gravity actuated means to cause said liquid switch means to assume a horizontal position, means initially holding said actuating circuit open, and time-controlled means actuated after said bomb comes to rest to lock said mount-

ing means against further movement relative to said bomb and to close said actuating circuit to said liquid switch means, whereby movement of said bomb thereafter will close said liquid switch means and operate said detonator.

2. A bomb comprising a detonator, an electric actuating circuit therefor including a mercury switch adapted to be closed in response to tilting from a horizontal position, gimbal means mounting said switch for universal movement, gravity actuated means to cause said switch to assume a horizontal position, a time switch initially holding said actuating circuit open, and time-controlled means operative after said bomb comes to rest to close said time switch and to lock said gimbal means against further movement relative to said bomb, whereby movement of said bomb thereafter will close said mercury switch and operate said detonator.

3. A bomb comprising a detonator, an electric actuating circuit therefor including a liquid switch adapted to be closed in response to tilting from a horizontal position, means mounting said switch for universal movement, gravity actuated means to cause said switch to assume a horizontal position, a normally open contact in circuit with said liquid switch, time-controlled means closing said last contact and locking said liquid switch against further movement relative to said bomb whereby movement of said bomb thereafter will close said liquid switch and operate said detonator, a radio receiver including a relay connected to close said actuating circuit, said receiver having means responsive to a predetermined received radio signal to energize said relay, time-controlled means for rendering said receiver operative to receive radio waves periodically for predetermined intervals of time whereby said bomb will be exploded upon reception of said predetermined signal during said operative periods, and additional time-controlled means connected to close said actuating circuit to operate said detonator after a predetermined number of such operative periods.

4. A bomb comprising a detonator, an electric circuit for firing the detonator, a first time-controlled means for conditioning the detonator circuit to be energized upon the movement of the bomb from its position of rest, a second time-controlled means for conditioning the detonator circuit to be energized upon receipt of a control signal from a remote point, and a third time-controlled means for conditioning the detonator circuit to be energized after the lapse of a predetermined time interval.

5. A bomb comprising a detonator, an electric

circuit for firing the detonator, a first time-controlled means for conditioning the detonator circuit to be energized upon the movement of the bomb from its position of rest after its release, a second time-controlled means for conditioning the detonator circuit to be energized during predetermined time intervals upon receipt of a control signal from a remote point, and a third time-controlled means for conditioning the detonator circuit to be energized at the termination of a predetermined number of such time intervals.

10 6. A bomb comprising a detonator, an electric circuit for firing the detonator, a plurality of switches selectively operable each to energize said circuit, means for conditioning the detonator circuit to be closed through one of said switches upon movement of the bomb from its position of rest, time-controlled means for closing the detonator circuit through a second of said switches upon the receipt of a radio control signal, and other time-controlled means for closing the detonator circuit through a third of said switches after the lapse of a predetermined time interval in the absence of a control signal.

15 7. A bomb comprising a detonator, an electric circuit for firing the detonator, a plurality of switches selectively operable at predetermined times each to energize said circuit, means for actuating one of said switches to thereby condition the detonator circuit to be energized upon movement of the bomb from its position of rest, the detonator circuit upon the receipt of a radio control signal, means for actuating another of said switches to close the detonator circuit after the lapse of a predetermined time interval in the absence of a control signal, and time mechanism controlling the operation of said switch actuating means in a predetermined time sequence.

20 8. A bomb comprising a detonator, an electric circuit for firing the detonator, a plurality of switches selectively operable at predetermined times each to energize said circuit, means for actuating one of said switches to thereby condition the detonator circuit to be energized upon movement of the bomb from its position of rest, a radio receiver having a relay which operates upon receipt of a predetermined radio signal to actuate another of said switches to close the detonator circuit, means for actuating another of said switches to close the detonator circuit after the lapse of a predetermined time interval in the absence of a control signal, and time mechanism controlling the operation of said switch actuating means in a predetermined time sequence.

JOHN HAYS HAMMOND, JR.
